United States Patent Office.

JOHN A. WHEELER, OF FREEBORN, MINNESOTA.

Letters Patent No. 77,557, dated May 5, 1868.

IMPROVEMENT IN WINDMILLS.

The Schedule referred to in these Letters Patent and making part of the same.

TO ALL WHOM IT MAY CONCERN:

Be it known that I, JOHN A. WHEELER, of Freeborn, in the county of Freeborn, and State of Minnesota, have invented a new and improved Windmill; and I do hereby declare that the following is a full, clear, and exact description thereof, which will enable others skilled in the art to make and use the same, reference being had to the accompanying drawings, forming part of this specification, in which—

Figure 1 represents a front view of my improved windmill.

Figure 2 is a longitudinal vertical section of the same, taken on the plane of the line $z z$, fig. 1.

Similar letters of reference indicate corresponding parts.

This invention relates to a new manner of hanging sectional sails in the frame of a windmill, and consists chiefly in the use of additional arms, which, in connection with the radial arms projecting from the shaft, serve as supports for the sectional sails, so that the same can be pivoted at right angles to the said radial arms, whereby the adjusting of the sails is greatly facilitated.

The invention also consists in the general arrangement and combination of devices for obtaining uniform motion and satisfactory results.

A, in the drawing, represents the horizontal shaft, which has its bearings in a disk or ring, B, that rests upon and turns loose on a suitable support, C, and that carries a vane, D, as shown.

On the outer end of the shaft A is mounted a hub, E, from the rim of which a suitable number of radial arms, F F, project. The arms F F are connected near their outer ends by means of band-rods G G, that are parallel to the tangents of the radii, which are equidistant between the respective pair of arms F.

Nearer to the hub, the arms F are connected by another set of band-rods, H H, which are parallel to the rods G, between each respective pair of arms F. On the rods G H are fitted a pair of adjustable eye-bolts, N N, between each pair of arms F, which bolts carry at their rear ends arms I I, which, in conjunction with the arms F, serve to hold the sectional sails J J, as is clearly shown in fig. 1.

Each sail consists of two or more sections, and each section is, by means of pins a a, pivoted between the arms F I. These pins are at right angles with the arms F, in which they have their bearings, and therefore not parallel with the band-rods G H. From that edge of each sectional sail which is nearest to the arm F to which the said sail is attached, projects forward a lug or ear, b, to the front end of which an eye, c, is pivoted, as shown in fig. 2. As the pins a are at right angles to the arm F, the edges near the said arm are in line, and therefore the lugs b and eyes c of each set of sails will be in line with each other, so that a rod, K, can be fitted through the said eyes of one set, in which it is clamped by means of set-screws d, or their equivalents, as shown in fig. 2.

The inner end of each rod, K is or may be pivoted to a bell-crank, f, which is hinged at its right angle to a cross, g, attached in front of the hub, while its other arm is, by means of a rod, h, connected with a sleeve, i, sliding on the shaft A, which sleeve can, by means of a lever, L, be moved forward or backward; thereby the sails can be adjusted so as to regulate the power of the mill, or to altogether stop the motion of the same. Thus, by means of the false arms I I, the sectional sails can be so hung as to be, in the aforesaid simple manner, connected with the sliding sleeve, whereby the position of the sails is adjusted.

Having thus described my invention, what I claim as new, and desire to secure by Letters Patent, is—

1. The false arms I I, secured by means of adjustable eye-bolts N N to the band-rods G H, so that the sectional sails J J can be pivoted between the radial arms F F and the false arms I I, all arranged substantially as herein shown and described.

2. The rods K, eyes c, and lugs b, in combination with the sectional sails J J, false arms I I, eye-bolts N N, band-rods G H, and radial arms F, all arranged and operating substantially as herein shown and described.

The above specification of my invention signed by me, this 25th day of February, 1868.

JOHN A. WHEELER.
